(57) **CLAIM**

The ornamental design for a menstrual device with holes and ridges, as shown and described.

DESCRIPTION

FIG. 1 is a front elevation view of a menstrual device with holes and ridges;

FIG. 2 is an isometric view of the menstrual device with holes and ridges;

FIG. 3 is an isometric view of the menstrual device with holes and ridges;

FIG. 4 is a rear isometric view of the menstrual device with holes and ridges;

FIG. 5 is an isometric view of the menstrual device with holes and ridges;

FIG. 6 is a top plan view of the menstrual device with holes and ridges; and,

FIG. 7 is a bottom plan view of the menstrual device with holes and ridges.

The broken line in FIG. 7 is included for the purpose of illustrating portions of the menstrual device with holes and ridges and forms no part of the claimed design.
